United States Patent Office

Des. 215,858
Patented Nov. 4, 1969

215,858

TABLE

John J. Hamilton, Cincinnati, Ohio, and Charles E. Schroer, Columbus, Ind., assignors to Hamilton Cosco, Inc., Columbus, Ind., a corporation of Indiana

Filed July 18, 1968, Ser. No. 12,818

Term of patent 14 years

Int. Cl. D6—01

U.S. Cl. D33—14

Fig. 2

Fig. 1

Fig. 3

Fig. 4

Fig. 5

Fig. 6

FIG. 1 is a top plan view of a table showing our new design;

FIG. 2 is a side elevation thereof;

FIG. 3 is a vertical section taken on the line 3-3 of FIG. 1;

FIG. 4 is a top plan view of a modified form of the table shown in FIG. 1;

FIG. 5 is a side elevation of the table shown in FIG. 4; and

FIG. 6 is a vertical section taken on the line 6-6 of FIG. 4.

We claim:

The ornamental design for a table, as shown and described.
